NON-JAMMING VIBRATORY HOPPER

Claude Maurice Owen, New York, N. Y., assignor to Chase Equipment Corporation, New York, N. Y., a corporation of New York

Application January 24, 1957, Serial No. 636,152

6 Claims. (Cl. 198—33)

This invention relates to a non-jamming vibratory hopper.

Hoppers of this type are usually employed as one unit of a series of units cooperating in the assembly and manufacture of a finished piece. It is a problem in such manufacturing operations to prevent the individual articles or objects, being separated within the hopper, from jamming whereby the feed to the balance of the units assembled in series would be interrupted. It being well understood that any interruption in this feed would result in an operational failure of the series of units and limit the productive efficiency and productive output of the entire unit.

In general, the hopper is fed by dumping into the hopper bowl a jumbled plurality or mass of articles or objects to be separated, either by means of a shovel or from a basket.

These articles are then, by various methods, separated individually and transported to another unit of the assembly line of units by suitable conveyors, chutes or runways.

It is a general problem in this type of arrangement to insure that the object being separated is in the correct position i. e., the correct side forward or the correct side up, so that it will be in the correct assembling position when introduced to a succeeding unit on the line of units. An object incorrectly positioned might possibly jam succeeding units thereby again reducing the efficiency and reducing the productive output of the entire series of units. Such costly delays and corresponding reductions in efficiency are extremely detrimental and it is to the solution of this problem that the instant application is directed.

It is an object of my invention to provide a non-jamming vibratory hopper wherein the articles will be rejected prior to their introduction into either a succeeding assembly unit or a runway chute or conveyor leading to a succeeding unit, when the objects so being separated are not in the correct feed position.

It is a further object of my invention to provide means for returning an object rejected because of incorrect position, to the hopper itself, where it will be reintroduced into the general mass for recycling.

It is still another object of my invention to provide means for pre-positioning the articles in advance of the rejecting means so that they will be positively positioned for rejection or acceptance by the rejection means.

It is yet another object of my invention to provide rejecting and pre-positioning means which will not damage or mar the article during the selection and rejection action.

It is still a further object of my invention to provide a stop which will prevent entry of an incorrectly positioned article into a succeeding assembly unit and will also position the article for positive ejection from that position, back into the mass contained within the hopper bowl.

It is still a further object of my invention to provide a non-jamming vibratory hopper which is simple and inexpensive to manufacture, easy to maintain, dependable in

2

operation and one which will afford the operator easy access in case of damage or improper operation.

Other objects and advantages of my invention will hereinafter appear in the following specification taken 5 together with the accompanying drawing forming a part thereof, in which:

Fig. 1 is a perspective view of my non-jamming vibratory hopper;

Fig. 2 is a top view of my non-jamming vibratory 10 hopper;

Fig. 3 is a partial sectional view taken along the line 3—3 of Fig. 2;

Fig. 4 is a partial sectional view of my non-jamming vibratory hopper showing in detail the rejecting apparatus;

Figs. 5, 6 and 7 are partial sectional views showing various consecutive stages of operation of a part of the rejection apparatus illustrated in Fig. 4;

Fig. 8 is a pictorial view of various shaped articles that 20 can be separated in my non-jamming vibratory hopper.

Referring to Fig. 1, there is shown a non-jamming vibratory hopper 10 including a fabricated hopper bowl 12, formed in a spiral, and a housing 14 which contains the drive motor for the vibratory hopper. The motors, contained within housing 14, are not shown; however, the drive for the reciprocating arm is a conventional gear head type motor operating at approximately 40 R. P. M. The vibratory hopper is powered by a magnet and leaf-spring arrangement, also conventional. Switch 16 on the 25 housing 14 is used to stop and start the motors and indicator knob 17 is provided to control the force of agitation of the hopper bowl about its vertical axis.

The motor drive shaft 18 protrudes slightly from the outside of one of the side walls of the hopper housing 30 and is connected to a crank 20 by welding or other suitable means so that as the shaft 18 rotates the crank 20 will rotate. To crank 20, by means of pin 22, is affixed the link arm 24 which, under the action of the rotating crank 20, moves backwards and forwards substantially 35 in the direction indicated by the arrow 26.

At the extremity of link arm 24, by means of pin 28, is affixed one end of a second crank 30. This crank is affixed at its other end by welding or other suitable means to the rod 32. Rod 32 at its lower extremity 32' is 40 journaled and supported in the bearing extension 34 of bracket 36 which is mounted on a side wall of the housing 14. Above extension 34 is a bronze thrust bearing 35 held in place by steel collar 35a which is fixedly mounted to rod 32 by set screw 35b. A second bracket 50 45 is also affixed to housing 14 has a bearing extension 40 which substantially cooperates with bearing extension 34 to support rod 32 in a vertical position.

Bracket 38 also has an upwardly extending portion 42 at whose upper extremity a rod 44 is mounted adjustably, and held in place by a set screw 43.

Rod 44 is bent in a substantially horizontal plane to form a U-shaped loop generally indicated at 46. On this rod loop 46 is mounted a plate member 48, by means of a loop guide 50 on plate extension 52, to one 60 side 46' of loop 46. The extension 52 is positioned beneath the rod loop at 46" so that the plate 48 is freely rotatable around the rod at 46' whereby it may move substantially upwardly. However, the extension portion 52 of plate 48 positioned below the rod at 46" prevents the plate from dropping below the substantially horizontal plane of the rod loop 46. Plate 48 has two 65 upwardly projecting extremities 54 and 56 for a purpose to be hereinafter described.

Rod 32, at its upper extremity 32", has an extension 70 arm 60 welded or by other suitable means affixed thereto. At the outer extremity of extension arm 60 (Fig. 4) is a plurality of openings 62, 62', 62" through which the

brush arm 64 extends substantially downward. These openings allow adjustable positioning of the brush arm. The brush arm illustrated in Figs. 1 and 4 is a coil spring wire, however, it being well understood that this brush arm could be composed of other suitable material without departing from the spirit of this invention.

This brush arm 64, extending through one of the openings 62, 62', 62'', is rigidly connected to the extension arm 60 by means of one of the set screws 66, 66', 66'' fitted in cooperating threaded holes at the side of extension arm 60. It is therefore seen that as the motor shaft 18 rotates it will cause, through the linkage hereinabove described, the arm 60 to vibrate as indicated by the arrow 68 (Fig. 2). This will make the lower extremity 64' of brush arm 64 move in a corresponding manner, as indicated by arrow 69 (Fig. 4), for a purpose to be hereinafter described.

On the interior of the vibratory hopper bowl, is a spirally wound shelf 70 (Figs. 2 and 4), upon which the articles 72, which are to be separated, are carried from the base 74 of the hopper around the side of the hopper bowl up to a position where they will be engaged by the brush arm 64.

The vibratory action which induces the movement of the article 72 from the floor of the hopper to the shelf 70 and thence upwardly, is conventional in the art and forms no part of the invention, and, therefore, will not be herein described.

An opening 80 in a side wall of the vibratory hopper bowl is provided to cooperate with a cup member 82 mounted on the hopper wall. Cup member 82 has two side walls 84 and 86, a back wall 88 and a bottom wall 90.

At a point short of the plate 48, shelf 70 terminates and becomes two parallel side walls 96 and 98 with an opening 100 therebetween forming a trackway. This trackway is removable and adjustable to provide a larger or smaller opening 100 so as to accommodate any desired size article. As the articles to be processed travel along the shelf 70, they drop into the trackway 96-98 supported on flange 72' of article 72 and the articles are carried along by vibratory action. A portion of the article 72 being transported will protrude into the opening 100 between the walls while another portion will ride above the trackway 96-98. As the article proceeds along, extensions 54, 56 of plate 48 insures pre-positioning of the articles 72 so that they are positively seated in one position or the other on their flanges 72'. Therefore, the article 72 will not appear canted as illustrated at 102, Fig. 4, but essentially vertical as shown at 104, 106, Fig. 4.

Plate 48 and extensions 54, 56 also insure a space between successive articles so that they will be more easily rejected if incorrectly positioned.

As the trackway 96-98 proceeds through coincident openings 107 (Fig. 4) in wall 84 of cup member 82, the wall 84 forms a stop to insure that articles will not proceed unless correctly positioned. This is done by providing a silhouette opening 108 through which an article positioned as at 104 would not be able to pass while an article positioned as at 106 would be able to pass.

As the articles are proceeding along trackway 96-98, they arrive in a position where the brush arm 64, which is vibrated substantially in the direction of arrow 69 (Fig. 4) under the action of the vibrating extension arm 60, will contact that portion of article 72 projecting above the horizontal plane of the upper trackway 96-98.

The extremity 64' of this brush arm, as shown in Figs. 5 through 7 inclusive, will eject from the trackway the article 72 if it is positioned as shown at 104 (Fig. 4), or 104' (Fig. 5). This is true because the portion of article 72 contained within the trackway 96-98 is substantially smaller than the opening 100 therebetween, and the side pressure of extremity 64' contacting the article 72, will eject it from between the walls.

In the event that this vibratory brush arm 64 should strike a piece 72 correctly positioned, i. e., as at 106 (Fig. 4), that portion of the article 72 which is supported beneath the horizontal plane of the upper edges 5 of these trackways, is substantially the same width as the opening 100 between the trackways, and, therefore, this spring motion will not force the object out and the object will be allowed to continue along its path as shown in Fig. 6. Objects positioned as shown at 106 10 (Fig. 4) will, therefore be allowed to pass through the opening 108 and will be projected through the chute 110 into connecting runways, conveyors, or conventional apparatus for conveyance to succeeding devices.

Articles which are ejected toward the hopper center 15 will fall down onto the hopper floor 74 to again begin the cycle up, through and around the shelf 70 back to the separating device hereinabove described. Articles ejected in the reverse direction, will strike wall 88 and slide down over bottom wall 90 of cup 82 thence to the 20 hopper floor 74 (Fig. 3) through opening 80.

As illustrated, the brush arm has a spring quality 25 therein and therefore will not mar or injure, by contact, the article 72 if the article 72 is rigidly seated and does not give against the pressure. In addition, the vibratory motion of the extension 64' will substantially be contacting, in correct cases, the smaller portion of the article being separated and, therefore, will have less chance of making a solid contact.

It being understood that should it be desired, or should 30 larger articles be separated than those shown, additional brush arms could be used having various designs which would accomplish the same result without departing from the spirit of this invention and likewise, different size or shaped openings 108 could be used.

In Fig. 7, it is shown that should a correctly positioned 35 article 72 happen to contact the brush arm extremity 64' directly in its path and tend to fall backward in the direction of the arrow 114, this would only be a momentary contact and would not be sufficient to tip the article 72 over backward. In the event, however, that the article actually was tipped over backward, it would be unable to pass through the opening 108. When so positioned and held by wall 84, it would be positively ejected by the vibratory action of the brush arm extension 45 64' during succeeding movement of the brush extremity 64'.

While I have shown what I believe to be the best embodiments of my invention, I do not wish however to be confined to the embodiments shown, but what I desire to cover by Letters Patent is set forth in the appended 50 claims.

I claim:

1. A vibratory non-jamming hopper adapted to separate a plurality of articles, the combination of a housing, 55 a hopper bowl mounted on said housing, means within said housing to vibrate the hopper bowl, rejecting means mounted on said housing adapted to reject incorrectly positioned articles in said bowl, first conveyor means within said bowl whereby the articles are conveyed from 60 the hopper bowl to the rejecting means by the vibratory action of the hopper bowl and second conveyor means connected to said first conveyor means adapted to carry off articles not rejected by said rejecting means, said rejecting means including selecting means to allow entry of 65 only correctly positioned articles into said second conveyor means, and pre-positioning means located in the path of the articles in advance of said rejecting means adapted to pre-position said articles for rejection by said rejecting means, wherein said first conveyor means includes a spiral shelf extending upwardly from the hopper bowl bottom around the interior of hopper bowl, said shelf terminating in advance of said pre-positioning means and a trackway extending from said shelf to said second conveyor means through said selecting means 70 75 and integral with said second conveyor means, said

trackway including two parallel side walls and an opening therebetween.

2. A vibratory non-jamming hopper adapted to separate a plurality of articles as in claim 1, wherein said pre-positioning means includes a bracket mounted on said housing, a first rod adjustably mounted on an upwardly extending portion of said bracket, said first rod being bent into a loop in a substantially horizontal plane and a plate member mounted on said rod loop adapted so that it can be pivoted upwardly but not downwardly about said rod, said plate member extending over said trackway.

3. A vibratory non-jamming hopper adapted to separate a plurality of articles as in claim 2, wherein said rejecting means includes rejected article directing means adapted to direct rejected articles back to the hopper bowl, said rejected article directing means including a cup member mounted on the hopper bowl, said cup member having two end walls, a back wall and a bottom wall and an opening in the side wall of the hopper bowl cooperating with said cup member.

4. A vibratory non-jamming hopper adapted to separate a plurality of articles as in claim 3, wherein said selecting means includes a silhouette opening in an end wall of said cup member in the path of said articles adapted to allow passage of only a correctly positioned article therethrough.

5. A vibratory non-jamming hopper adapted to separate a plurality of articles as in claim 3, wherein said rejecting means includes a second rod, means for mount-

10 5 ing said second rod substantially vertically, means for inducing reciprocating movement of said second rod, a laterally extending arm fixedly mounted at the upper extremity of said second rod, removable brush means downwardly extending from said arm and mounting means adapted to mount said brush means to said arm in a pre-selected position.

6. A vibratory non-jamming hopper adapted to separate a plurality of articles as in claim 5, wherein said brush mounting means includes a plurality of openings in the lateral extremity of said arm and an adjustable fastening screw cooperating with each opening, and said brush means includes a coil spring having one extremity passing through at least one of said openings in the lateral extremities of said arm, said other extremity of said coil spring positioned above said trackway adapted to move back and forth across said trackway to reject an article as said arm moves in response to said reciprocating second rod.
